UNITED STATES PATENT OFFICE.

JACOB KALAYJIAN, OF PASADENA, CALIFORNIA.

IRONING BOARD.

Application filed October 13, 1927. Serial No. 225,945.

The present invention is directed to improvements in ironing boards.

The primary object of the invention is to provide a device of this character so constructed that it can be conveniently folded in a wall cabinet when not in use and readily unfolded when required for use.

Another object of the invention is to provide a device of this kind constructed in such manner that the board when unfolded for use can be swung to various angles in a horizontal plane to suit the convenience of the user.

Another object of the invention is to provide a device of this type wherein the main ironing board has associated therewith a sleeve board capable of being compactly folded with the main board.

In the accompanying drawings:

Figure 1 is a vertical sectional view through the device, showing it in its operative position.

Figure 2 is a similar view showing the device in its folded or inoperative position.

Figure 3 is a view looking into the wall cabinet, showing the ironing board in its folded position.

Figure 4 is a sectional view on the line 4—4 of Figure 1.

Referring to the drawing, 1 designates a wall cabinet which has its side frames 2 provided with diametrically oppositely disposed vertical grooves 3, the purpose of which will appear later.

The main ironing board 4 has connected to its inner end by a pivot bolt 5 a substantially triangular shaped plate 6 which lies upon the upper surface of the board, said plate having an arcuate slot 7 formed transversely therein and in which the clamping bolt 8 engages, said bolt being supported in an opening 9 formed in the board 4.

The rear end of the plate has formed integral therewith a cross bar 10, the ends of which are provided with trunnions 11 which are slidably engaged in the grooves 3.

In order to hold the board 4 in its operative position, a brace leg 12 is provided and has its upper end pivotally connected to the under surface of the board 4 by brackets 13, the lower end of the brace having an eye 14 carried thereby for engagement with the stud 15 carried by the bottom of the cabinet.

Having its rear end connected to the rear wall of the cabinet by a hinge 16 is a sleeve board 17, said board having a bail 18 pivotal-

ly connected thereto adapted to engage the board 4 to hold the sleeve board in its operative position when desired.

A door 19 is provided to close the cabinet and conceal the board when not in use. 60

As shown in Figure 1 the board 4 is in its operative position, at which time the trunnions 11 of the bar 10 engage the upper ends of the grooves 3 in order to maintain the board in a horizontal position, the brace 12 serving as a fulcrum to prevent tilting of the board. It will be obvious that since the brace 12 is pivotally engaged with the stud 15 that the board 4 can be swung laterally upon loosening the bolt 8 to the position desired 70 after which the bolt is clamped to maintain the board in rigid condition. When it is desired to fold the board the outer end is grasped and moved upwardly, whereupon the trunnions will ride downwardly in the 75 grooves 3 until the board assumes the position shown in Figures 2 and 3 of the drawings. The sleeve board 17 may be readily brought into use upon swinging the same downwardly in order that the bail 18 will rest 80 upon the board 4, as shown in Figure 1.

The plate 6 not only serves as means for pivotally connecting the ironing board, but also constitutes a rest or holder for the iron.

In order that the sleeve board 17 can be 85 swung laterally with the board 4, a bolt 17' is connected to the hinge 16.

The inner end of the board 4 is provided with a reduced extension 20 adapted to pass through the tapered recess 21 formed centrally in the cross bar 22 which is fixed to the rear wall of the cabinet 1. It will be obvious that when the board 4 is swung downwardly to its operative position the extension 20 will pass upwardly through the recess. This extension, will, when the board is swung laterally, rest upon the bar 22 and will prevent the inner end of the board from moving downward when pressure is applied adjacent the inner end thereof. Of course when it is 100 desired to fold the board the extension will be brought into registration with the recess to permit the same to pass downwardly there-through when the board is swung upwardly.

Having thus described the invention, I 105 claim:

A device of the class described comprising a cabinet having grooves in its side frames, a plate having a cross bar carried thereby, the ends thereof slidably engaging 110

the grooves, an ironing board having its rear end pivotally connected to the plate for movement in a horizontal plane, a cross bar fixed in the cabinet and having a recess formed therein, an extension carried by the ironing board, said extension being adapted for passage through the recess, whereby

when the board is swung in a horizontal plane the extension will engage the upper surface of the second named cross bar, as and for the purpose set forth. ¹⁰

In testimony whereof I affix my signature.

JACOB KALAYJIAN.
